UNITED STATES PATENT OFFICE.

EDWARD F. CARRY, OF CHICAGO, ILLINOIS.

DRAFT GEAR.

Application filed October 10, 1925. Serial No. 61,717.

The invention relates to draft gears designed to absorb the energy exerted by the drawbars of railway cars, and has for its principal object to dampen the shocks of recoil incident to the pull and thrust of the drawbar upon the springs of the gear through the medium of a liquid agent operating to supplement the springs in their resistance to draft and buffing movements.

The invention further consists in certain other novel details of construction and combinations and arrangement of parts, preferred embodiments of which are shown on the accompanying drawing, in which—

Fig. 1 is a longitudinal sectional view of the gear with the several parts in their normal positions taken on line 1—1 of Fig. 2.

Fig. 2 is a horizontal plan view showing portions of the underframe in section and the gear in assembled position with the draft lugs on the center sills;

Fig. 3 is a view similar to Fig. 1, but showing the port closing position of the piston during a buffing operation with the front spring expanded and the rear spring in compression;

Fig. 4 is a dual view showing at the left a front end view of the gear assembled with the underframe of the car and at the right a vertical transverse sectional view through gear and underframe taken on line 4—4 of Fig. 1 looking in the direction indicated by the arrows;

Fig. 5 is a vertical section taken on line 5—5 of Fig. 3 looking in the direction indicated by the arrows showing the combined air and liquid chamber and the piston chamber below it; and

Fig. 6 is a rear view taken on line 6—6 of Fig. 1 showing the gear supported in position between the draft castings on the underframe, looking in the direction indicated by the arrows.

In the drawings, 10 represents an underframe having the usual center sills 11 to which are secured the customary draft castings 12. Between and in engagement with the draft castings is the draft gear 13 of my invention, comprising a spring and liquid casing 14 and a removable cross head portion 15. The casing 14 is provided at its rear end with a head 16 preferably integral therewith, the front portion of the casing being open to permit access to the interior thereof. The removable head portion 15 covers the opening in the casing to confine therein movable gear elements herein-after to be described, and is held to the casing in any approved fashion, preferably by stud bolts 17 threaded into the casing above the bottom thereof and by headed bolts 18 taking the casing flange 19 and the head 15, all of said bolts being held against rotation in any approved manner.

The gear as a whole is supported in position by a tie plate 20 spanning the distance between the draft castings 12 and a supplemental plate 23 shaped to the contour of the underside of the gear casing 14. Each of these plates is secured to the outwardly extending flanges 21 of the draft castings 12 by means of bolts 25, arranged along the respective margins of said plates. The tie plate 20 engages the front head 15 and adjacent portion of the casing 14, while the supplemental plate 23 supports the rear end 16 of said casing, by virtue of which the whole gear is held in operative position between front and rear lugs 26 and 27 of the draft castings 12. To insure effective transmission of draft and buffing stresses to the underframe and to avoid possible lost motion between the draft gear and the front and rear lugs 26 and 27 of the draft castings 12, I provide a wedge key 28 designed to compensate for possible variation in length of draft gear unit or distance between the lugs 26 and 27 of the draft castings. A wedge key is positioned preferably between the front lug 26 of each draft casting 12 and adjacent face 31 of cross head 15 and is held from displacement by a rib or ribs 32 on the inclined face 30 of the key interlocking with similar ribs 33 on the correspondingly inclined contiguous face 31 of the cross head 15. These wedge keys function to establish and maintain positive draft and buffing relation between the draft gear unit and underframe since by the operation of gravity they automatically adjust themselves to the space between the lugs 26 of the respective draft castings and adjacent face 31 of the cross head 15, rendering the gear unit interchangeable with those now in service and permitting the use of the same draft gear equipment.

The draft gear casing 14 and the cross head 15 when assembled as before described, contain all of the moving parts of the gear as will be obvious from an inspection of

The draft gear casing 14 and the cross head 15 when assembled as before described, contain all of the moving parts of the gear as will be obvious from an inspection of

the drawings. The casing 14 houses a piston rod 35 adapted to reciprocate in cylindrical chamber 36 of the casing and fitted with head 37 provided with annular grooves 5 designed to receive suitable liquid retaining rings. The piston head is seated with a drive fit upon a reduced portion 38 of piston rod 35 and is held from longitudinal movement in one direction on the rod by shoulders 42 on the rod and in the opposite direction by retaining nut 41 providing abutments for the piston head. The piston head 37 divides the cylindrical chamber 36 into front compartment 39 and rear compartment 40 containing respectively the flat volute springs 43 and 44 arranged on opposite sides of the piston head and seated against the respective sides of the piston head and front and rear ends 15 and 16 of the casing. Above chamber 36 of the casing 14 is a combined liquid and air chamber 34 separated from compartments 39 and 40 by a partition 29 having front and rear ports 45 and 46 communicating respectively with said compartments and containing, if desired, needle valves 47 adjustably mounted in the upper wall 48 of the casing. The valves are manually operable and independently adjustable to control the rate of flow of the liquid from one compartment of the chamber 36 to the other and thru the liquid and air chamber and are provided with thickened shank portions 49 threaded into supporting bushings 50 secured in the upper wall 48 of the casing and reduced stem portions registering with port openings 45 and 46 in partition 29. An opening in the upper wall 48 of the casing provides ready access to the liquid and air chamber 34 for the introduction of air and liquid to the casing and is closed by plug 51 threaded into the opening.

The piston rod 35 has a sliding bearing in packing screw 53 and bushing 52 respectively let into the front and rear portion of the cross head 15, suitable packing 69 being interposed to provide a liquid tight joint where the piston rod passes out of the casing 14. The packing screw head 54 is shaped to provide a series of spaced lugs 55 on the periphery of the head adapted to accommodate a spanner wrench (not shown) for use in tightening the packing screw 53 upon the packing 69. The packing screw is held from reverse rotation by means of a locking piece 56 having a lug 57 projecting upwardly from the base of the piece and adapted to be lodged between a pair of the peripheral lugs 55 on the head of the packing screw. The locking piece 56 is removably fixed in position by means of a stud bolt or cap screw 58 threaded into the underside of the cross head 15 as best shown in Fig. 1. The piston rod 35 is also provided with drawbar coupling 59 for connection with the usual drawbar 60 by coupling pin 61 having

its head 62 let into one of the jaws to clear the upper wall of the cross head 15.

The drawbar coupling 59 is guided in its movements within the cross-head 15 to insure against distortion in the piston rod 70 and prevent injury to the packing screw 53 caused by side thrusts from the coupler when positioned at an angle to line of draft. To facilitate movement between drawbar coupling 59 and top, bottom and side walls, 63, 75 64 and 65, it may be desirable to provide for the lubrication of these members through the medium preferably of oil grooves 67 in the top and side walls to distribute the flow of oil issuing from drain hole 68 of the oil and waste pan 66 formed in the top wall of the cross head. 80

With the gear mounted in position on the underframe access to the needle valves 47 and to casing plug 51 may be had thru opening 8 in the car floor 9, and the casing may be drained by removing drain plugs 7 closing openings in the bottom of chamber 36, as best shown in Fig. 1. 85

Assuming the parts to be in the normal position shown in Fig. 1 of the drawing, liquid is poured into the casing thru opening in the top wall of the casing to fill compartments 39 and 40 and as much more liquid as may be required to only partially fill the liquid and air chamber 34 in order to provide for a substantial volume of air above the liquid level for a purpose to be described. 90

In operation, a buffing shock will cause the piston to move in the direction indicated by the arrows in Fig. 1. The speed and extent of this movement will depend upon the energy applied at the drawbar and the resistance offered by the liquid and spring contained in compartment 40 and by the compression of the air in chamber 34. The piston movement will result in the displacement of the liquid in compartment 40 and cause it to be forced through port 46 at a rate of flow proportioned to the magnitude of the energy driving the piston. This flow of the liquid under pressure will meet with a resistance commensurate with the speed of the piston and the acceleration of the flow of liquid thru said port will increase that resistance until the energy driving the piston is spent. During such movement of the piston, the liquid displaced will flow into the chamber 34 and the liquid in said chamber will be forced thru a second port 45 into the expanding front compartment 39 to further increase the resistance to the flow of the liquid and therefore to piston movement. Continued movement of the piston will bring the piston head 37 within the area of port 46 and in the path of the liquid passing thru it, causing a progressive reduction of the port opening and consequent throttling of the liquid flowing thru that 105 110 115 120 125 130

port, ultimately checking further movement of the piston.

It will be noted that in the present embodiment of the invention the volume of liquid displaced in compartment 40 exceeds the capacity of the expanding front compartment 39 to receive it because of the presence in the latter compartment of the piston rod 35. Since the quantity of liquid to be expelled from compartment 40 is about equal to that contained in the space between the retaining nut 41 and the rear head 16 of the casing, and as this space is not diminished by any piston rod volume as in the case of the other compartment, it is evident that a given movement of the piston and a corresponding increase in the length of compartment 39 will cause a greater amount of liquid to be forced thru port 46 into chamber 34 than would be drawn from said chamber into compartment 39, the excess accumulating in the chamber 34 to build up a flexible resistance thru the increasing compression of the air confined in said chamber. Continued movement of the piston will cause an additional length of piston rod volume to enter compartment 39 thus further reducing the capacity of that compartment to accommodate all of the liquid expelled from compartment 40, causing further accumulation of excess liquid in the air and liquid chamber 34 and a proportionate increase in the compression of the air volume in said chamber. This operation may be continued until the piston head 37 completely covers the port 46 of compartment 40 when the entrapped liquid in said compartment will check further movement of the piston. Until the piston completely closes the port 46 and communication between chamber 34 and compartment 40 is interrupted, the compressed air volume in the liquid and air chamber will operate to cushion the piston to prevent the too sudden checking of its movement as it approaches the port closing position.

With the piston in the port closing position indicated in Fig. 3, and with spring 44 compressed under the stress of piston movement, the expansive force of the spring will start the piston back to its normal balanced position but since the piston can move as fast only as the liquid drawn into expanded compartment 39 and expelled from compartment 40 can flow thru the respective ports, the spring will release its energy without recoil and the gear parts will be restored to their original position without shock or other disturbing vibrations.

It will be noted that the gear functions to afford a high resistance to buffing operations and lesser opposition to draft strains, thereby greatly increasing the starting torque of the train power unit by reducing the force required to take up the slack between the

cars of the train, but in either direction of movement the gear parts will be controlled by the rate of flow of the liquid from one compartment to the other through the air and liquid chamber 34, whether induced by forces applied at the drawbar or the released energy of the compressed spring elements within the gear, and the rate of flow may be regulated and established by the manipulation and setting of the needle valves in the air and liquid chamber, their proximity to the liquid ports in the path of the liquid stream regulating the speed of the liquid thru said ports or, if valves are not desired, such rate of flow may be regulated by the size, shape or number of the port openings communicating with the respective compartments.

In the construction described the impact of buffing operation will be resisted by the spring, liquid and compressed air elements found in the gear, but under draft movements only the spring and liquid elements will function to absorb the stresses of operation. This condition is brought about by the difference in the capacities of the compartments at opposite sides of the piston head due to the presence in one of them (compartment 39) of the piston rod 35 the bulk of which displaces an appreciable quantity of the liquid contained in said compartment, and since a given movement of the piston in a direction opposite to that indicated by arrows in Fig. 1 will cause a smaller volume of liquid to be forced out of the contracting compartment 39 into air and liquid chamber 34 than the quantity drawn from said chamber into the expanding compartment 40 the level of the liquid in chamber 34 will fall and the air trapped in said chamber will expand and be rendered ineffective to restrain movement of the piston in that direction, leaving the burden of the pulling strain to be resisted by the spring and liquid elements alone.

From the foregoing disclosure it will be evident that provision is made for the proper absorption of the forces created by the swift initial movements of the piston in both draft and buffing operations with means for progressively increasing the resistance to piston movement as the piston approaches a port closing position. From this it is obvious that to cushion the initial shocks of impact or draft the liquid ports 45 and 46 should be of such size or number as to permit the instantaneous transfer of the liquid in either compartment 39 or 40 to the air and liquid chamber 34 and to the other compartment. It will also be evident that due to the use of a single combined air and liquid chamber common to both compartments 39 and 40, it is possible to equalize the resistance to both draft and buffing movements of the piston and compensate for the piston rod

volume in compartment 39 by increasing the capacity of said compartment or reducing that of the other compartment, as desired.

What I claim is:—

- 5 1. A draft gear comprising a housing containing a piston chamber, a piston reciprocable in said chamber, springs on opposite sides of said piston, an air and liquid chamber, ports connecting both chambers and in communication with opposite sides of said piston, and manually operable valve means within said liquid and air chamber adapted to control one of said ports. 70
- 10 2. A draft gear comprising a housing containing a piston chamber, a piston reciprocable in said chamber, springs on opposite sides of said piston, an air and liquid chamber, ports connecting both chambers and in communication with opposite sides of said piston, and manually and severally operable valves within said liquid and air chamber adapted to control said ports. 75
- 15 3. A draft gear comprising a housing containing a piston chamber, a piston reciprocable in said chamber and dividing the chamber into compartments, springs in said compartments on opposite sides of said piston, an air and liquid chamber, ports connecting both chambers and in communication with said compartments, and port controlling valves supported within said air and liquid chamber adapted for manipulation outside said chamber. 80
- 20 4. A draft gear comprising a housing containing a piston chamber, a piston reciprocable in said chamber, a liquid and air chamber, ports connecting both chambers and in communication with opposite sides of said piston, and manually operable needle valves adapted to control said ports. 85
- 25 5. A draft gear of the class described comprising a piston chamber, a piston reciprocable in said chamber, a combined liquid and air chamber above and in communication with the opposite sides of the piston in the piston chamber, and valves in said liquid and air chamber adapted to control the flow of liquid in either direction of piston movement. 90
- 30 6. A draft gear comprising a piston chamber, a piston reciprocable in said chamber and dividing the chamber into compartments, springs in said compartments on opposite sides of said piston operable to normally hold the piston in its balanced position, and a single combined liquid and air chamber in communication with said compartments, the air volume in said last mentioned chamber being in excess of that required to provide for piston displacement. 100
- 35 7. In a draft gear the combination comprising a piston chamber and a piston movable therein and dividing said chamber into compartments a single chamber containing liquid and an air volume and communicating with said compartments through ports on opposite sides of said piston, the air volume in said last mentioned chamber being in excess of that required to provide for piston displacement, said air volume being adapted for compression to oppose movement of the piston in one direction and rendered ineffective to restrain movement thereof in the opposite direction. 105
- 40 8. A draft mechanism comprising a piston chamber, a piston dividing the chamber into compartments, a single chamber containing liquid and an air volume and communicating with said compartments thru ports arranged on opposite sides of said piston, the air volume in said last mentioned chamber being in excess of that required to provide for piston displacement, and means for progressively increasing compression of the air volume by piston movement in one direction and rendering said air volume ineffective to oppose movement of said piston in the opposite direction. 110
- 45 9. In a draft gear comprising a piston chamber, a piston reciprocable in said chamber and dividing the chamber into compartments, a single chamber containing liquid and an air volume and having port connection with said compartments, the air volume in said last mentioned chamber being in excess of that required to provide for piston displacement, and means adapted to compress the air in said chamber during piston movement in one direction and render said air volume ineffective to oppose movement of said piston in the opposite direction. 115
- 50 10. A draft gear comprising a piston chamber, a piston reciprocable therein and dividing said chamber into compartments, a single chamber containing liquid and an air volume and having port connection with said compartments, the air volume in said last mentioned chamber being in excess of that required to provide for piston displacement, and means adapted to increase the flow of liquid to said chamber to compress the air in said chamber during piston movement in one direction and cause the recession of the liquid in said chamber to render said air ineffective to oppose movement of said piston in the opposite direction. 120
- 55 11. A draft gear comprising a chambered casing and a front crosshead portion removably secured to said casing, and a piston reciprocable in said casing and provided with a drawbar coupling slidably mounted in said crosshead, and a drawbar pivotally connected to said coupling, said connection being adapted for movement within said crosshead. 125
- 60 12. The combination with the underframe and draft castings of a railway car, of a draft gear assembly comprising a chambered casing and a front crosshead portion removably secured to said casing, a piston re- 130

- 5 ciprocable in said casing and provided with a drawbar coupling slidably mounted in said crosshead, shock-absorbing elements within said casing, and wedge key elements 5 between said crosshead and the draft castings of the underframe whereby draft and buffering stresses applied at the drawbar coupling are transmitted thru the gear assembly to said underframe.
- 10 13. A draft gear comprising a chambered casing and a front crosshead portion removably secured to said casing, a piston reciprocable in said casing and provided with a drawbar coupling slidably mounted in said crosshead, and coupling lubricating means in said crosshead comprising an oil and waste pan formed on said crosshead, oil grooves in the top and side walls of the crosshead, and an oil drain communicating 20 with said grooves and pan.
14. The combination with the underframe of a railway car, of a draft gear assembly, and wedge key elements between said underframe and draft gear assembly whereby 25 draft and buffering stresses are transmitted thru the gear assembly to said underframe, said wedge key and draft gear assembly having interlocking engagement one with the other to prevent displacement of said 30 keys.
15. A draft gear comprising a piston chamber, a piston reciprocable in said chamber and dividing the chamber into compartments, and a combined liquid and air chamber common to said compartments, the air volume in said last mentioned chamber being in excess of that required to provide for 35 piston displacement.
16. In a draft gear the combination comprising a piston chamber and a piston movable therein and dividing said chamber into compartments, of a combined liquid and air chamber communicating with and overlying said compartments, the air volume in 40 said last mentioned chamber being in excess of that required to provide for piston displacement.
17. In a draft gear the combination comprising a piston chamber and a piston movable therein and dividing said chamber into compartments, a combined air and liquid chamber in communication with and overlying said compartments, the air volume in 45 said last mentioned chamber being in excess of that required to provide for piston displacement, and a liquid in said chamber and compartments, the liquid in said chamber constituting a liquid head common to the liquid in said compartments.
- 50 18. A draft gear of the class described comprising a piston chamber, a piston reciprocable in said chamber, a combined liquid and air chamber above and in communication with the opposite sides of the piston in the piston chamber, and valves 55
- adapted to control the flow of liquid in either direction of piston movement.
19. A draft gear comprising a housing containing a piston chamber, a piston reciprocable in said chamber, a liquid and air chamber, ports connecting both chambers and in communication with opposite sides of said piston, and valves adapted to control 70 said ports.
20. A draft gear comprising a housing containing a piston chamber, a piston reciprocable in said chamber and dividing the chamber into compartments, springs in said compartments on opposite sides of said piston, an air and liquid chamber, ports connecting both chambers and in communication with said compartments, and port controlling valves. 75
21. A draft gear comprising a housing containing a piston chamber, a piston reciprocable in said chamber, springs on opposite sides of said piston, an air and liquid chamber, ports connecting both chambers and in communication with opposite sides of said piston, and manually and severally 80 operable valves adapted to control said ports. 90
22. A draft gear comprising a housing containing a piston chamber, a piston reciprocable in said chamber, springs on opposite sides of said piston, an air and liquid chamber, ports connecting both chambers and in communication with opposite sides of said piston, and manually operable valve means adapted to control one of said ports. 95
23. A draft gear comprising a housing containing a piston chamber, a piston reciprocable in said chamber, springs on opposite sides of said piston, an air and liquid chamber, ports connecting both chambers, and in communication with opposite sides of said piston, and valve means controlling one of said ports. 100
24. A draft gear comprising a housing containing a piston chamber, a piston reciprocable in said chamber, springs on opposite sides of said piston, an air and liquid chamber, ports connecting both chambers and in communication with opposite sides of said piston, and valves presenting deflecting surfaces to oil entering the air and liquid chamber through the ports. 105
25. A draft gear comprising a housing containing a piston chamber, a piston reciprocable in said chamber, springs on opposite sides of said piston, an air and liquid chamber, ports connecting both chambers and in communication with opposite sides of said piston, and means adjacent said 110 ports for deflecting entering oil currents. 115
26. A draft gear comprising a housing containing an air and liquid chamber, a piston chamber, a piston reciprocable in said chamber, ports connecting both chambers and in communication with opposite 120
- 125
- 130

sides of said piston, and needle valve means adapted to control said ports.

27. A draft gear comprising a housing containing a piston chamber, a piston reciprocable in said chamber and dividing the chamber into compartments, springs in said compartments on opposite sides of said piston, an air and liquid chamber, ports connecting both chambers and in communication with said compartments, and port controlling valve means mounted for manipulation outside of said chamber.

28. The combination with the underframe of a railway car, of a draft gear assembly, and wedge key elements between said underframe and draft gear assembly, said wedge key and draft gear assembly having

interlocking engagement one with the other to prevent displacement of said draft gear assembly.

29. The combination with the underframe and draft castings of a railway car, of a draft gear assembly including a front cross-head portion, and wedge key elements between said cross head and the draft castings of the underframe, said wedge key and front crosshead portions having complementary ribs interlocking one with the other to connect said draft gear assembly and underframe.

In witness whereof I have hereto set my hand this 6th day of October, 1925.

EDWARD F. CARRY.
